UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

977,019.

Specification of Letters Patent. Patented Nov. 29, 1910.

Application filed August 19, 1910. Serial No. 577,940.

To all whom it may concern:

Be it known that I, ALFRED G. F. KUROWSKI, a citizen of the United States, residing in the borough of Brooklyn, city of New

5 York, in the county of Kings and State of New York, have invented certain new and useful Improvements in Type-Writing Machines, of which the following is a specification.

10 This invention relates to line-spacing mechanisms, and especially to devices for advancing the platen through part of a line space to enable the printing of characters, or symbols, etc., below the usual writing 15 line on the work sheet.

In printing the denominators of fractions below the line of writing, difficulty has been encountered, because of the necessity of advancing the platen by hand more than half 20 of a line space, so that the types would print below the divisor-lines, and of holding the platen steady, against the tension of the usual spring detent, while striking the keys.

The main object of this invention is to 25 enable denominators or other subscripts to be readily printed below the writing line. This is done by mechanically advancing the platen through more than half a line space; and retaining it where adjusted; the usual 30 spring detent being rendered ineffective to complete the rotation of the platen through an entire line space. A dog or tooth is forced into engagement with the space wheel to advance the platen as required, and the 35 usual spring detent is automatically cast off from the line-space wheel.

In the accompanying drawings, Figure 1 is a perspective, showing one form of the invention applied to an Underwood writing 40 machine. Fig. 2 is a side view, the device being idle. Fig. 3 shows the device in use.

A platen 1 is fast on an axle 2, journaled in platen frame ends 3, and is line-spaced by a lever 4 through a slide 5 and pawl 6, the 45 latter driving a toothed wheel 7 fixed on the axle. A spring detent 8 engages the wheel 7. The usual releasing lever 9, (Fig. 1), loose on the axle, is rocked to cast off the detent, when it is desired to write on ruled 50 lines, etc.

Type bars 10, carrying types 11, strike against the platen, certain of said types preferably being made smaller than the ordinary lower case types, and arranged near 55 the outer ends of the bars, as at 11^a, to form

exponents or fraction numerators, which strike the platen only when the latter is in upper case position to print above the usual writing line.

By swinging forwardly the handle 12 of 60 a finger lever, pivoted at 13, a plate or broadened end 14, forming the opposite arm of the lever, is rocked from its idle position (Fig. 2) to its active position, (Fig. 3) to enter a tooth 15, carried thereby, between 65 any two adjacent teeth of the wheel 7 and advance the platen part of a regular line space so that the exponent types 11^a or other types, shall strike below the usual line of writing (and sometimes directly beneath the 70 exponents previously printed as in the case of fractions).

A stop 16 on the handle 12 arrests the latter by striking one end edge of a slot 17 when the platen has been advanced more 75 than half a line space; at which time the tooth 15 may stand about in line with the pivot 13 of the lever and the axle 2, (see Fig. 3).

The platen remains in the Fig. 3 position 80 during the operation of the type keys, without the necessity of the operator retaining his hold on the lever 12; since a spring 18 (which normally holds the lever 12 against accidental displacement) is too weak to rotate the platen. A pin 21 on the detent 8 normally rests in a recess 22 in the broadened end 14 of the lever, one wall 23 of which recess forms a cam, which leads to a dwell portion 19 forming an arc about concentric with the pivot 13 and preferably constituting one wall of a slot 20. The lever on its initial stroke causes the cam 23 to disengage the pin and detent from the wheel, the pin riding onto the dwell 19 to hold the detent 95 disengaged, while the line space wheel is turned by the dog 15. By relieving the wheel of the pressure exerted by the detent, danger is avoided of the platen being turned through an entire line space by the detent 100 settling into the next notch. The slot 20 is of sufficient width to accommodate the throw of the pin when cast off by the usual detent-releasing lever 9. When the lever 12 is moved back toward its idle position, to release the tooth 15 from the wheel, said tooth starts the platen toward initial position. 105

Having thus described my invention, I claim:

1. In a typewriting machine, the combination 110

- tion with a platen, line-space mechanism therefor including a notched or toothed wheel connected with the platen, and a detent engaging the wheel, of a tooth to turn the wheel and platen through part of a line-space, a vibratory finger lever controlling the tooth, and a cam controlled by the lever to cast off the detent on the initial stroke of the lever.
10. 2. In a typewriting machine, the combination with a platen, line-space mechanism therefor including a notched or toothed wheel connected with the platen, and a detent engaging the wheel, of a tooth to turn the wheel and platen through part of a line-space, and a vibratory finger lever controlling the tooth and having a recess to accommodate a pin on the detent, one wall of the recess operating to cast off the detent on the initial stroke of the lever, and a dwell por-
- tion to which the wall of the recess leads to hold the detent disengaged.
3. In a typewriting machine, the combination of a platen, a notched or toothed wheel connected with the platen, a detent to engage the wheel, said detent having a pin, a finger lever having a tooth to turn the wheel through part of a line-space, said lever having a cam recess, one wall of which bears against the pin on the detent to cast off the detent, a dwell portion forming one edge of the slot and connected to the wall of the recess to hold the detent disengaged, one end of said slot being enlarged to accommodate the throw of the pin when cast off by the releasing lever.

ALFRED G. F. KUROWSKI.
